UNITED STATES PATENT OFFICE.

EDWARD R. AMMON, OF READING, PENNSYLVANIA.

PATTERN-PLATING ATTACHMENT FOR CIRCULAR-KNITTING MACHINES.

Application filed October 30, 1924. Serial No. 746,760.

My invention relates to circular knitting machines, and particularly to plating attachments therefor; my main object being to provide an improved device which will 5 automatically control the laying of a plating yarn or its idle float in the production of novel pattern designs as governed by a special jacquard pattern drum mechanism; my improvements are adaptable for producing any variable pattern design of regular or irregular outline, extending vertically, horizontally, or inclined to the wales, and in a simple and positive manner as 10 more fully described in connection with the accompanying drawings showing a preferred embodiment thereof, while the novel features are particularly pointed out in the subjoined claims.

In the drawings:

20 Fig. 1 is mainly a side elevation of a known type of knitting machine embodying my improvements.

Fig. 2 is a plan view of the same, parts being broken away to more clearly show the 25 essential construction.

Fig. 3 is a fragmentary detail view showing the jacquard drum and connected operating parts.

Fig. 4 is an enlarged fragmentary view 30 showing in vertical section a portion of the knitting head and the cooperative relation of my plating yarn guide.

Fig. 5 indicates a stocking having a pattern design producible with my improvements.

In the drawings I have indicated a Scott and Williams knitting machine, more fully set out in Patent No. 1,152,850 of September 7, 1915, but my improvements are applicable to any knitting machine having a 40 rotated needle cylinder and a plurality of yarn guides; the machine illustrated being well known both as to construction and operation and needing but brief description 45 to make clear the application and operation of my improved attachment thereto.

In the drawing 5 represents the machine frame, 6 the rotated needle cylinder, 7 the cam ring, 8 the main drive shaft, and 9 the 50 sector shaft forming an axle to carry the usual intermittently actuated cam drum 10 loosely mounted thereon. A plurality of yarn guides 11 are commonly employed, pivotally swingable into and out of yarn-feeding position as effected by a corresponding plurality of push rods 12, the move-

ments of the latter being controlled as heretofore by cam drum 10. The operation of the machine is well known and where plating is desired, two yarn guides are commonly lowered into feeding position, the needles operating on both, and one yarn being laid so as to appear on the surface of the fabric hiding the knitted-in second 60 yarn.

My improvements are applicable to any knitting machine having the above characteristics and the preferred embodiment shown in the drawings will now be described.

In place of one of the regular guides 11, I employ a special plating guide 15, preferably mounted in an extension 16 of the regular guide bracket 17, and intermediate pivoted at 18 in said extension, 70 as shown, so that the lowered apertured yarn-carrying end 19 will swing transversely above the needle cylinder 6. The swing of said guide 15 is limited as shown by contact of its upward end 20 either 80 against a fixed stop 25 of extension 16, or a spaced movable stop 26, said stops being shown in the form of set screws for accurately adjusting such limited guide swing.

The guide 15 is swung into and out of yarn 85 feeding position in the usual manner, as determined by cam drum 10, by a push rod 12^a; a special push rod 30, also actuated by said drum 10, however first acting through bell crank lever arm 31, pivoted at 32, to 90 swing stop 26, carried by the other arm 33 of said lever, away from guide end 20, thus permitting movement of said guide by rod 12^a. Guide 15 is under tension of spring 34 normally tending to hold same in lowered 95 yarn feeding position above the needles, said spring yielding however under action of push rod 12^a, to permit guide movement to non-feeding position, and also yielding under action of rod 35, hereinafter more fully 100 described, to permit limited guide movement between stops 25 and 26.

This limited guide movement between 105 said stops 25 and 26, provides in well known manner for carrying the plating yarn to idle float position inside the needle cylinder, disclosing on the fabric surface the single main yarn of the second feeding guide employed in plating knitting; and by employing contrasting colors in the two guides and 110 controlling the feed floating movement of guide 15, pleasing varieties of pattern de-

signs may be produced. My main object is to positively and automatically control said movements in producing determined pattern effects, and to accomplish this I employ 5 the following mechanism.

Secured to the machine frame 5, and projecting therefrom is an end bracket 40, rigidly supported by a leg 41, and preferably further stiffened, as shown, by an angular 10 bracket extension 42 which in the machine shown, may be readily secured to the frame boss forming an end bearing for sector shaft 9. A similar bracket 45, supported on legs 46, is rigidly held in spaced relation to 15 bracket 40 by a connecting bar 47, and its angular bracket extension 48 carries a rigid bar 49, the opposite end in the present construction, being readily held, within cam drum 10 in the opposite frame bearing for 20 sector shaft 9.

Rotatably mounted in said end brackets, are two shafts 50 and 51 each having an end gear wheel marked respectively 52 and 53, and suitably connected as shown through 25 a train of gears to main shaft 8; in the construction shown, such connection being readily made to gear 60 of said Scott patent, and shaft 50 is timed to rotate one revolution for each rotation of the needle cylinder.

30 Slidably keyed to shaft 50 as shown is my special jacquard pattern drum 55 later herein more fully described, and closely embracing the same in an open traversing frame comprising end members 65, 66 connected by rods 67, 68; said end members being centrally apertured and loosely strung upon shaft 50, and the tie rods holding the end members in close contact with said drum, but permitting free rotation of the 40 latter.

End member 65 is formed at one end with a threaded half-nut 70 adapted to engage a thread 71 cut on shaft 51, or a sleeve secured to the latter; and said nut is normally 45 retained in such engagement by a weight 72, or the like, hung on the opposite end of member 65. The rotation of threaded shaft 51 will, through the engagement of said half-nut 70 of the traversing frame, longitudinally progress said jacquard drum 55 along its shaft 50 in one direction; and reverse drum movement is simply effected, as shown, by a weight 75 flexibly connected to end member 65. Weight 75 is effective 50 only upon disengagement of nut 70, and the latter is preferably automatically disengaged, as shown, by a cam 76 on drum 10 which at the proper time is adapted to rock the traversing frame sufficiently to disengage 55 said nut 70 from said threaded shaft 51. Riding upon the drum 10 in the path of cam 76 is a tensioned lever 77 pivotally carried by rock shaft 78, which latter is rotatably mounted at one end in a bracket 60 79 fixed to bar 49, and its opposite end, in

the construction shown, readily engaged in a recess formed in the end of comb stud 450 of said Scott patent; and said shaft 78 carries an arm 80 positioned within the limits of longitudinal movement of the drum 70 and adapted to bear upward on traversing frame rod 67 to rockingly free nut 70 of the latter.

Mounted on connecting bar 47 are spaced blocks 85 and 86 formed with bearings for a rock shaft 87, the latter carrying fixed levers 88 and 89. Lever 88 is formed with a jacquard drum contacting end 90, and bracket 85 has a forked-end extension 91 engaging lever 88 to steadily hold the 80 same and permit only movement in a plane radial to shaft 87. Lever 89 is yieldingly connected to the free end of rod 35 pivotally secured to the end 20 of special yarn guide 15; such guiding connection, as shown, 85 comprising springs 92 and 93 strung upon said rod and seating on opposite faces of the apertured end of the latter through which said rod loosely projects, adjustable collars 95 and 96 providing for variation of said 90 spring tension.

The jacquard pattern drum employed is preferably of a length sufficient to control all the plating movements throughout the length of a stocking, avoiding any repeat 95 pattern when desired; each drum rotation, as previously stated, corresponds with a rotation of the needle cylinder, while its longitudinal feed is such that the contact end 90 of lever 88 will engage a new circumferential path at each drum rotation. The drum surface may be made up in any manner, but I prefer to employ sectional cast plates, the surface thereof having rises and depressions for effecting determined 100 guide movements.

The operation of my attachment will be readily understood from the foregoing description, the action of the pattern drum 55 on yarn guide 15 being secondary to the action of drum 10 controlling its feeding and non feeding movements. Yarn changes of the main yarn may be effected as heretofore without interference, and during the reciprocative heel and toe movements the drum would continue to operate, but, as usual, both the main yarn and plating yarn would then be thrown out and other yarn substituted.

110 My attachment is simple and effective for any variety of pattern, irrespective of the courses or wales of the fabric, and moreover may be readily attached to the machine with but slight changes and at little cost. And while I have described a specific embodiment thereof, changes may be made as for instance the drum-contacting finger may be made to traverse longitudinally instead of the drum. Other modifications and changes 115 may also occur and I do not desire to limit 120

myself to the specific construction shown and described.

What I claim is:—

1. In combination with a circular knitting machine having a circular series of needles, knitting cams therefor, and a plurality of pattern controlled yarn guides; a plating yarn guide movably mounted to swing radially above said circle of needles, pattern mechanism controlling the feeding and non-feeding positions thereof, and a separate jacquard pattern drum mechanism, adapted to impart radial pattern plating movements to said plating guide when the latter is in yarn feeding position, comprising a drum, means to rotate the latter, means to progressively move said rotated drum longitudinally in one direction and freely in the reverse direction, pattern means controlling such longitudinal movements, an arm ac-

tuated by said drum, and means connecting said arm and plating guide.

2. In combination with a circular knitting machine having a circular series of needles, knitting cams therefor, and a plurality of pattern controlled yarn guides; a plating yarn guide, a pivotal mounting therefor adapted to swing said guide radially across the needle circle, pattern mechanism adapted to control the feeding and non-feeding positions of said guide, a separate jacquard pattern drum mechanism adapted to impart pattern plating swings to said guide when the latter is in yarn-feeding position, a fixed stop, and a cooperating stop movable into and out of the path of said guide to limit said pattern-plating swings.

In testimony whereof I affix my signature.

EDWARD R. AMMON.
